CHANGE MAKER AND CIRCUIT THEREFOR

Clifford B. Adams and Fred E. Wallin, St. Louis,
Mo., assignors to National Rejectors, Inc., St.
Louis, Mo., a corporation of Missouri

Application June 25, 1948, Serial No. 35,158

5 Claims. (Cl. 194—10)

1

This invention relates in general to coin devices and more particularly to a change making mechanism and an associated circuit for controlling vending machines, which machines are adapted to vend units of merchandise or service. The machine will respond to the deposit of coins of larger denominations than the value of said unit by virtue of a coin changing device which automatically operates the vending machine to deliver one unit of value and automatically returns to the depositor the proper change in coins of predetermined denomination.

Vending machines incorporating change making apparatus in use by the public prior to this invention contained inherent defects which mitigated against their general acceptance and satisfactory operation. It is not uncommon for coins, particularly those coins slightly deformed or having debris or adhesive material on their surfaces, to lodge upon the coin switches in the coin changer, thus causing a surplus amount of change to be returned to the depositor, or delivery of a surplus number of vended units.

Another difficulty arises when the supply of change coins in the machine is insufficient to supply proper change to a depositor when the machine is operated by a coin larger than the predetermined unit value. These and other disadvantages are completely overcome in the present invention, the solution of which comprises important objects of the invention.

A further object of the invention is the provision of impact means for replenishing the supply of unit coins for change making purposes from the coins deposited.

Another object of the invention is the provision of automatic switching means, including an electric circuit in the vending machine for rendering the device inoperative when the machine is either sold out or otherwise inoperative, and automatically returning the deposited coins to the user.

A further object of the invention is the inclusion of relay means responsive to the coin switches for rendering the change making device inoperative and automatically converting the vending machine for operation with coins of unit value when the device has insufficient coins therein to make proper change.

Another object of the invention is the provision of a manually restorable relay responsive to the permanent closure of the coin switches for de-energizing the change making device, including other circuit means for conditioning the vending machine to operate with coins of unit value.

2

These and other objects of the invention will be apparent in one embodiment described and shown in the following specifications and drawings in which:

5 Fig. 1 is a front elevation of the change making device.

Fig. 2 is a rear elevation of the device shown in Fig. 1.

Fig. 3 is an enlarged fragmentary elevation of 10 the lower portion of the device shown in Fig. 1 with parts removed.

Fig. 4 is the same as Fig. 3 with certain elements in changed position.

Fig. 5 is a cross-sectional plan view taken 15 through section line 5—5 Fig. 3.

Fig. 6 is a fragmentary cross-sectional view taken through section line 6—6 Fig. 3.

Fig. 7 is a cross-sectional view taken through section line 7—7 Fig. 6 showing the path of travel 20 of change coins.

Fig. 8 is a fragmentary cross-sectional plan view of the device taken generally through section line 8—8 Fig. 3.

Fig. 9 is a fragmentary cross-sectional view of 25 the device taken through section line 9—9 Fig. 8.

Fig. 10 is a fragmentary cross-sectional view of the device taken through section line 10—10 30 Fig. 3.

Fig. 11 is a schematic diagram of the electrical 35 circuit for the change making device and the operative electric components of a typical vending machine.

In order to simplify the description and focus 40 the features of the invention it is assumed that 35 a typical vending machine is adapted to operate upon the deposit of a U. S. 5¢ coin, that the change making device will accept the deposit of U. S. 10¢ and 25¢ coins, and that the change returned will be in coins of 5¢ denomination.

Referring to Fig. 1, a frame 1 serves as a housing for the change making device and a combination slug rejector and coin sorter 2, which is shown positioned in the upper portion of the frame. All coins deposited are directed by means 45 not shown into a single entry 3.

The change making mechanism 4 is positioned in the frame 1, directly beneath the coin sorter 2 as shown. The coin sorter has a rejection passageway 5, for guiding non-acceptable or rejected coins into a return chute 6, the lower end of which is connected to a return cup not shown. A cylindrical storage magazine 7 is positioned in the change maker for retaining 5¢ coins in a horizontal stacked relation, subject to being dispensed from a bottom opening therein.

The rear view Fig. 2 illustrates various elements in their proper working relation, including the anticoins dispensing relay 8, coin rejecting electromagnets 9, 10 and 11, master vending switch 12, 10¢ coin switch 13, 25¢ coin switch 14, 10¢ and 25¢ safety switch 15, and motor holding switch 16.

The change maker is operated by an electric motor 17 having a self-contained speed reducer secured to frame 1 with a drive shaft 18 projecting through the frame as shown in Fig. 1. A magazine empty switch 19 is positioned in frame 1 having an operating lever 20, normally urged into contact with the lower 5¢ coins in the magazine. When the magazine has a pre-determined minimum of coins therein the switch lever 20 will move inward and operate a control circuit. Chute 21 integral with frame 1 is provided to collect and conduct acceptable gravity propelled coins into a cash box not shown.

Referring to Fig. 3, drive shaft 18 has integrally mounted thereon a toothed wheel 22 for sequentially restoring a discharging means for discharging 5¢ coins. A cam 23 for operating switches 15 and 16 is secured to shaft 18 in timed relation with wheel 22. A restoring cam 24 secured to the inside face of, and in timed relation with, wheel 22 is provided to initiate the restoration of coin switches 13 and 14 and to operate safety switches 25 and 26. Switch 16 is secured to frame 1 directly behind switch 25. The para-magnetic switch levers 13a and 14a when moved to their lowermost position by the downward travel of the 10¢ and 25¢ coins respectively will be temporarily held in displaced position by the magnetic attraction of permanent magnets 152 and 153 secured in the frame 1, as shown Figs. 2 and 3.

A cam lever 27 is pivotally secured to frame 1 by shoulder screw 28. A torsion spring 29 having its opposite ends secured to the screw 28 and lever 27 respectively, normally urges the lever in a direction shown by arrow. The lower extremity of lever 27 is a cam follower 30, positioned for engagement and movement by the rim of cam 23. The upper end of lever 27 has secured therein a pin 31, which pin is adapted to engage a cam surface 32 on a cradle member 33. Said cradle is pivotally secured to the frame by stud 34. Cradle 33 has a pair of integrally spaced projections 35 and 36 extending through clearance apertures in frame 1 for sequentially operating switches 15 and 16 when the cradle is rotated.

A lever 37 is pivotally mounted to frame 1 by stud 38 and has its lower end 39 adapted to engage cam 24. A spring 40 having one end secured to lever 37 and its opposite end to frame 1 is provided to normally bias the lever in the position shown Fig. 3. A pin 41 integral with the upper end of lever 37 is adapted to engage cam surface 42 of lever 43, which lever is pivotally mounted on stud 34 to frame 1. A projection 44 of lever 43 is positioned through a clearance aperture in frame 1 to release operating lever 13a of switch 13 when lever 43 is rotated. The opposite end 45 of lever 43 is positioned to operate the lever 25a of switch 25 when the lever 43 is rotated. A second pin 46 secured in lever 37 is adapted to engage cam surface 47 of lever 48. The lever 48 is pivotally mounted to frame 1 on stud 49 and adapted to rotate when lever 37 is operated. A projection 50 integral with lever 48 extends through a clearance aperture in frame 1 to displace lever 14a of switch 14 when the lever 48 is rotated. The opposite end 51 of lever 48 is positioned to operate lever 26a of switch 26 when the lever 48 is rotated.

51 of lever 48 is positioned to operate lever 26a of switch 26 when the lever 48 is rotated.

Fig. 4 illustrates the position of levers 27 and 37 when operated by their respective cams 23 and 24, the movement of lever 27 imparts rotation to cradle 33, the projectors 35 and 36 of which will operate switches 15 and 16. The movement of lever 37 will cam the levers 43 and 48 from the positions shown in Fig. 3 to positions shown Fig. 4 and sequentially operate switches 25 and 26. The movement of levers 43 and 48 will also sequentially dislodge levers 13a and 14a of switches 13 and 14.

The change coin storage magazine 7 is secured to a coin discharge base plate 52. An electromagnet 53 is secured to frame 1 with its armature 54 positioned as a latch urged into position, shown Fig. 3, by spring 55 to serve as a lock for releasing the coin discharge means to be herein-after described.

The cross-sectional view 5 illustrates the relative position of the principal elements immediately below the coin sorter 2. Since the combination coin rejector and sorter 2 is well known in the art, detailed description will be omitted, except to point out that acceptable coins of 5¢, 10¢ and 25¢ denomination are conducted in separate chutes directly above passageways 56, 57 and 58 for conducting 5¢, 10¢ and 25¢ coins respectively into the change maker. These chutes are formed by partitions 59, 60 and 61, secured in spaced relation to the frame 1.

The cross-sectional view shown Fig. 6 illustrates the continuance of coin passageways 56, 57 and 58 through the change maker. A hopper 62, positioned to frame 1, is used to guide all acceptable coins from lower exits of passageways 56, 57 and 58 into chute 21. The crank levers 12a, 13a and 14a of switches 12, 13 and 14 project through appropriate clearance openings into the above passageways. Crank lever 12a is responsive to the descent of each coin of each denomination, whereas lever 13a is positioned to be responsive to the descent of each 10¢ coin only descending in passageway 57 and lever 14a is positioned to be responsive to the descent of each 25¢ coin descending in passageway 58.

The cross-sectional view Fig. 7 indicates the internal construction of passageway 56 and its relation to magazine 7. The partition member 59 connects the magazine 7 through a rectangular opening 63 therein for the passage of 5¢ coins from passageway 56 into magazine 7. A rebound anvil 64, having its upper surface obliquely positioned to the entrance of passageway 56, is secured by rivets 65 to partition 59 for causing 5¢ coins to rebound from the upper surface of the anvil into the magazine as shown in dotted lines. The 5¢ coins will, by gravity, fall into the magazine in stacked relation as indicated. However, when the magazine is filled, surplus coins are blocked from entering the magazine and will fall into passageway 56 as indicated and be conducted by hopper 62 into chute 21.

This construction eliminates the conventional and complicated electro-magnetic sweep normally employed above coin hoppers to prevent jamming when they are filled.

The coin discharge apparatus is shown in the cross-sectional views Figs. 8, 9 and 10, wherein the magazine 7 is supported to frame 1 by base plate 52. A coin discharge slide 66, having a thickness slightly less than the thickness of a 5¢ coin, is positioned for reciprocating motion beneath plate 52 between the latter and the frame 1. The slide

has a tongue 67 projecting upwardly through an aperture 68 in plate 52 for latching engagement with armature 54 of electro-magnet 53 shown in engagement with the tongue 67 in Figs. 3 and 9. Pins 69 secured in plate 52 serve as guides for the end of armature 54. A pair of ears integral with slide 66 project upwardly through a clearance aperture 71 in plate 52. A pin 72 through ears 70 supports roller 73, which roller is positioned for intermittent engagement with teeth 74 of wheel 22. Springs 75, each secured at one end to frame 1 and each having its opposite end secured to pin 72 normally urge the slide 66 towards its discharge position. A circular coin discharge exit 76 is positioned in the frame 1 at a proper distance from the axis of the magazine 7. An elongated aperture 77 is provided in the slide 66 directly beneath magazine 7 when the slide is in latched position as shown Figs. 8 and 9. An ejection spring 78 is secured to plate 52 by rivets 79 having an offset portion 80 normally extending downward through aperture 71 in a slot 81 in slide 66.

It is now apparent that the lowermost coin in the magazine 7 will rest in the coin aperture 77 against the upper surface of frame 1 and when the armature 54 is withdrawn by electro-magnet 53 the springs 75 will move the slide 66 into its discharge position with aperture 77 coinciding with exit 76. Under these conditions the offset portion 80 of spring 78 will force the coin downward into a return cup not shown. It is apparent that the next lowermost coin in magazine 7 will be moved by gravity into aperture 77 only when the slide 66 is returned to its latched position as shown Fig. 9 and that for each reciprocal movement of slide 66 a coin will be discharged through the exit 76.

The magazine empty switch is clearly shown in Fig. 10 with its lever 20 normally held downward by a predetermined number of coins in the lower portion of the magazine 7. When the magazine contains a predetermined minimum number of coins, the lever 20 will move to the position shown in dotted lines, by the action of a spring within the switch 19.

The schematic diagram Fig. 11 shows the control circuits for both a typical vending machine and the change device, and for clarity the upper dotted enclosure 82 indicates the circuit and electrical components usually a part of the vending machine. The lower dotted enclosure 83 is the circuit and the electrical components of the change making device.

Safety relay 84 is provided to protect the vending machine under certain conditions to be hereinafter described and is provided with a manually releasable latch 85 which will hold the armature blade 86 in displaced position following the momentary energizing of its coil.

Lamp 87 is provided and adapted to be illuminated to indicate that the vending machine is empty. "Use nickel only" lamp 88 is provided and adapted to be illuminated when the coin storage magazine is empty.

Relay 89 is responsive to the deposit of coins to operate the vending machine. The rectangular symbol 90 represents an electric motor or other magnetic means for operating the discharge mechanism of the vending machine.

L_1 and L_2 represents a source of electric energy and conductor 91 connects the normally open switch blade 92, one terminal of magnetic means 90, blade 93 of empty switch 94, terminal 95 of master vending switch 12, one terminal of relay

coil 8, one terminal of motor 17, and terminates by connection to one terminal of change slide electro-magnet 53.

Conductor 96 from power source L_2 connects normally closed blade 97 of relay 84 and one terminal of lamp 87. Switch blade 98 of relay 84 is connected by conductor 99 to the remaining terminal of lamp 87 and to normally open switch blade 100 of switch 94. Armature blade 86 of relay 84 is connected to one terminal of relay coil 84 by conductor 101 and the remaining terminal of relay coil 84 is connected by conductor 102 to the normally open blade 103 of delivery switch 104. Conductor 101 also connects armature blade 86 with normally open blade 105 of relay 89, one terminal of relay coil 89, one terminal of the 10¢ electro-magnet 10, blade 106 of relay 8, and terminal 107 of switch 16. Terminal 108 of switch 16 is connected by a conductor 109 to the remaining terminal of electro-magnet 53, normally closed terminal 110 of switch 25 and normally closed terminal 111 of switch 26. Conductor 112 connects terminal 113 of switch 16 to the remaining terminal of motor 17. Terminal 114 of switch 26 is connected to the normally open terminal 115 of switch 14. Conductor 116 connects terminal 117 of switch 25 to normally open terminal 118 of switch 13. Conductor 119 connects normally closed terminal 120 of switch 13 to terminal 121 of switch 14. Terminal 122 of switch 14 is connected by conductor 123 to armature blade 124 of relay 8. A latch 125 is positioned to engage and hold blade 124 after relay coil 8 is energized. Blade 126 of relay 8 is connected by a conductor 127 to terminal 128 of switch 19. Blade 129 of relay 8 is connected by a conductor 130 to terminal 131 of switch 19 and one terminal of lamp 88. Blade 132 of relay 8 is connected to terminal 133 of switch 13 by conductor 134. Terminal 135 of switch 19 is connected to one terminal of the 25¢ electro-magnet 11. Terminal 136 of switch 15 is connected to one terminal of the 10¢ electro-magnet 9. The remaining terminals of magnets 9 and 10 are connected together by conductor 137. Terminal 138 of switch 15 is connected by conductor 139 to the remaining relay terminal of the 5¢ electro-magnet 10 and to blade 140 of relay 89. The remaining terminal of relay coil 89 connects through conductor 141 to blade 142 of relay 89 and to terminal 143 of switch 12. Blade 144 of relay 89 is connected by conductor 145 to the remaining terminal of the magnetic means 90. Armature blade 146 of relay 89 is connected by conductor 147 to blade 148 of switch 104. Blade 149 of switch 104 is connected by conductor 150 to blade 151 of switch 94 and to the remaining terminal of lamp 88.

In operation the elements of the vending machine and change maker are illustrated in rest position, Figs. 1, 2, 3 and 11. Assuming that an acceptable 5¢ coin is deposited in entry 3, Fig. 1, it will be tested and sorted by the combination rejector and sorter 2 and will descend by gravity into the 5¢ passageway 56 of the change maker, shown Figs. 5, 6 and 7. In descending the coin will first impinge upon and displace lever 12a of the master vending switch 12 and momentarily close a circuit between terminals 95 and 143 of said switch, shown Fig. 11, which will operate the vending machine to deliver one unit of value, as will be hereinafter described.

Referring to Fig. 7 and assuming that the change coin storage magazine 7 is empty or par-

initially filled, the 5¢ coin descending in passageway 56 will impinge upon the upper surface of anvil 64 and rebound therefrom through opening 63 and fall into magazine 7 in horizontal stacked position. It is apparent that the 5¢ coins deposited in the machine will first be directed to the storage magazine 7 in order to maintain an adequate supply of change coins and in the event the magazine 7 is filled, the coins will be blocked from entering opening 63 and will descend directly into chute 21 and thence into a cash box not shown.

Referring to Fig. 11, when the vending machine and change maker are in rest position, a circuit is normally established through magnet 10 from line L₂, conductor 96, blades 86 and 97 of relay 84, conductor 101, conductor 139, blades 140 and 146 of relay 89, conductor 147, blades 148 and 149 of delivery switch 104, conductor 150, through blades 151 and 93 of empty switch 94, through conductor 91, to the line L₁. When the magnet 10 is energized, it will withdraw a projection, not shown, in the rejector 2 and permit a 5¢ coin to descend into passageway 56 of the change maker. In the event that the machine is caused to be inoperative through various conditions to be hereinafter described, magnet 10 will not be energized and its said projection will cause any 5¢ coin deposited therein to be bypassed into passageway 5 and thence into return chute 6.

When the master vending switch 12, Fig. 11, is momentarily closed by a 5¢ coin, a circuit will be established from L₁ through conductors 91 and 141, through relay coil 89, conductor 101, closed blades 86 and 97 of relay 84, through conductor 96, to the line L₂. When the relay 89 is thus momentarily energized, its blades 142 and 146 will establish a holding circuit through coil 89, conductor 147, closed blades 148 and 149 of delivery switch 104, through conductor 150, closed blades 151 and 93 of empty switch 94 and through conductor 91 to line L₁. Simultaneously a circuit will be closed through the magnetic means 90 to operate the vending machine one cycle by virtue of conductors 91 and 145 and the now closed blades 105 and 144 of relay 89 to conductor 101. Through the use of well known means not shown the delivery of one unit of value or service will cause a switch 104 to be momentarily operated. This operation will break the circuit through blades 148 and 149 to release relay 89 to its rest position, shown Fig. 11, thus completing one delivery cycle of the vending machine.

In the event the vending machine is empty, switch 94 will be operated by means not shown, thus temporarily holding open the circuit to relay 89 and preventing its further operation.

Simultaneously a circuit will be established through the empty signal lamp 87 from L₁, conductor 91, now closed blades 93 and 100 of switch 94, conductors 99 and 96 to the line L₂. Under these conditions the lamp 87 will be illuminated and the 5¢ reject magnet 10 will be de-energized by virtue of the open blades 93 and 151 and thus reject all 5¢ coins deposited. It is also to be noted that magnets 9 and 11 are positioned in the rejector to reject 10¢ and 25¢ coins when de-energized. It will, therefore, be apparent that all coins deposited under the above conditions will be rejected when the empty switch 94 is operated.

In the event that a 5¢ coin, debris, or other cause, holds master switch 12 in closed position, one unit of value will be dispensed from the vending machine as previously described. How-

ever, the operation of delivery switch 104 will complete a circuit from conductor 91 through terminals 95 and 143 of switch 12, conductor 141, through closed blades 142 and 146 of relay 89, through conductor 147, through closed blades 148 and 103 of delivery switch 104, conductor 102, through relay coil 84, through closed blades 86 and 97 to conductor 96. This circuit will energize relay coil 84 and operate relay 84, thus causing its armature to be latched open by latch 85. This movement of blades 86 and 97 will open the circuit to relay 89 and magnetic means 90, thus rendering the vending machine inoperative until the switch 12 is opened and latch 85 manually released.

In the event that a 10¢ coin is deposited in entry 3, the vending machine will operate one cycle to deliver a unit of value and the change maker will discharge one 5¢ coin as change in the following manner.

Referring to Figs. 5 and 6, an acceptable 10¢ coin will descend in passageway 57 and first impinge upon and momentarily operate lever 12a of master vending switch 12. This action, by means of a circuit previously described, will operate the vending machine one cycle and deliver one unit of value. As the coin descends in passageway 57 it will impinge upon and displace lever 13a of switch 13, which lever will remain temporarily displaced by the attraction of the permanent magnet 152, Figs. 2 and 3.

Referring to Fig. 11, the operated switch 13 will simultaneously close circuits through motor 17 and electro-magnet 53, through conductor 101, normally closed blades 132 and 136 of relay 8, conductor 134, the now closed terminals 118 and 133 of switch 13, conductor 116, terminals 117 and 110 of switch 25, and conductors 109 and 91. The instant electro-magnet 53 is energized its armature 54, shown Figs. 3 and 9, will release slide 66 under the influence of springs 75 to discharge the lowermost coin in the magazine 7 through exit 76. Spring 78 will insure the discharge of the coin by virtue of the downward pressure of offset portion 80.

It is to be noted that a circuit through the motor 17 is initially made through terminals 108 and 113 of switch 16 and through terminals 110 and 117 of safety switch 25. Thus when the 10¢ switch 13 is temporarily closed, the motor 17 will start and cause rotation to shaft 18, shown Fig. 3, which rotation will move cam 24 into engagement with the lower end 39 of lever 37. Continued movement of the cam 24 will cause lever 37 to move counterclockwise about its stud 38 against the restraining bias of spring 40. The movement of pin 41 in lever 37 against cam surface 42 will impart counterclockwise movement to lever 43. The first movement of the lever 43 will move its projection 44 upward and disengage lever 13a of switch 13 from magnet 152, thus restoring the 10¢ coin switch to normal rest position. Slightly further movement of lever 43 will operate lever 25a of safety switch 25.

Again referring to the elements as shown in Fig. 3, it is apparent that the initial movement of shaft 18 resulting from the deposit of a 10¢ coin will cause cam 23 to engage cam follower 30 of lever 27 to move the lever clockwise about its shoulder screw 28 against the biasing action of spring 29. The movement of lever 27 will cause its pin 31 to engage cam surface 32 of cradle member 33 and rotate the cradle in a counterclockwise direction about its stud 34. Projection 36 of cradle 33 will immediately en-

gage lever 16a and operate motor holding switch 16. In a predetermined sequence cradle projection 35 will engage lever 15a and operate switch 15, which will open terminals 138 and 136 thereof and de-energize reject magnets 9 and 11, thus rejecting any 10¢ and 25¢ coins deposited during the operation of the change maker.

The deposit of either 10¢ or 25¢ coins through circuit means, shown Fig. 11, and cam means, shown Fig. 3, will cause the drive shaft 18 to 10 complete one revolution for each coin deposited by virtue of the operation of the motor holding switch 16.

Referring to Figs. 3, 4, 8, and 9, following the deposit of a 10¢ coin, the rotation of shaft 18 will begin, as previously described, and one tooth 74 of wheel 22 will engage roller 73 secured to the slide 66 and restore the slide from its discharge position to the position shown Fig. 3, where it will be relatched by armature 54, thus permitting the next lowermost coin in the magazine 7 to descend into the slide aperture 77, shown Figs. 8 and 9.

Referring to Fig. 11, following the closure of the 10¢ switch 13, the motor holding switch 16 will be operated by projection 36, shown Fig. 4, and thus maintain a circuit to the motor 17 through the closed terminals 107 and 113 of switch 16 and conductors 101 and 91. Upon the completion of one revolution of the shaft 18, the holding switch will open to stop the motor by the operation of cam 23 and cam follower 30.

Thus it is apparent that under normal conditions the deposit of a 10¢ coin will operate the vending machine one cycle and discharge one 5¢ coin as change, and following this operation the device will come to rest and assume its normal rest position as indicated Figs. 3 and 11.

In the event that the coin switch 13 remains closed because of a suspended coin or debris, or other causes, and is not opened by projection 44, the change making device will be prevented from operating a second time by the action of safety switch 25, which is caused to operate by lever 43 immediately following the restoration movement of projection 44.

When switch 25 is operated while switch 13 is in displaced position, a circuit will be completed from conductor 101, blades 106 and 132 of relay 8, conductor 134, through terminals 133 and 118 of the now closed coin switch 13, conductor 116, through the now closed terminals 117 and 154 of safety switch 25, conductor 155, through relay coil 8, to conductor 91. Under these conditions relay coil 8 will be energized and the relay latched open by latch 125. Thus blades 106 and 132 will de-energize the circuit to the motor 17 and stop the change maker from further operation. Simultaneously a circuit will be established through the "use nickel only" lamp 88 from conductor 101 through blades 106 and 129 of relay 8, conductor 130, through lamp 88, conductor 150, blades 151 and 93 of switch 94 to conductor 91. Illumination of lamp 88 will signify that 5¢ coins only should be deposited. It is apparent that any subsequent 10¢ or 25¢ coins deposited will be rejected because of the open circuit to the reject magnets 9 and 11 resulting from the opening of blades 124 and 126 of relay 8. In order that the change making device be returned to normal operating condition, the cause of the permanent closure of the coin switch 13 must be removed and the relay 8 manually unlatched.

When lever 37 is moved to a predetermined

position, its lower pin 46 will engage cam surface 47 and move lever 48 counterclockwise about stud 49. The first movement of lever 48 will cause projection 50 to strike lever 14a when displaced and held by magnet 153, to restore the said lever and its switch 14 to normal position. Further movement of lever 48 will cause its end 51 to engage lever 26a and operate switch 26. The function of the two last mentioned switches will be hereinafter described.

When the vending machine and change making device are in normal rest position, the 10¢ and 25¢ reject magnets 9 and 11 remain energized by virtue of a circuit supplied by closed blades 140 and 146 of relay 89, conductor 139, the closed terminals 138 and 136 of switch 15, conductor 137, and the closed terminals 135 and 128 of switch 19, conductor 127 and closed blades 124 and 126 of relay 8, conductor 123 and the normally positioned coin switches 14 and 13, through conductor 119, conductor 134, closed blades 132 and 106 of relay 8, to conductor 101. The completion of this circuit permits the free passage of 10¢ and 25¢ coins through the coin sorter 2.

Under the assumption that the vending machine and change maker are in rest position, as shown Fig. 11, and a 25¢ coin is deposited in entry 3, it will be sorted by sorter 2 and descend in passageway 58 and first operate switch 12, which will cause the vending machine to function in the manner previously described to deliver one unit of value. Further descent of the 25¢ coin will displace lever 14a and operate switch 14 and since lever 14a will be temporarily retained by magnet 153, the motor 17 and electro-magnet 53 will be energized in the same manner as when a 10¢ coin was deposited, thus starting the cycle of the change maker. Motor holding switch 16 will be operated and cause the motor to operate for sufficient time to complete one revolution of its shaft 18 by virtue of cam 24, lever 27, Fig. 4.

When the electro-magnet 53 is energized the slide 66, Fig. 4, will discharge one 5¢ coin through exit 76, as shown Fig. 9. Immediately following the above operation the toothed wheel 22 will rotate and three of the teeth 74 thereon will successively reciprocate the slide 66 to discharge three additional 5¢ coins, which completes the change cycle. At this point projection 50 of lever 43 will engage and release lever 14a of switch 14 from permanent magnet 153, thus de-energizing magnet 53, causing the coin slide 66 to remain latched and completing the discharge of change coins. The motor 17 will continue the rotation of shaft 18 until projection 36 of cradle 33 releases the motor holding switch lever 16a, thus restoring the change making device to its normal rest position.

As in the case of the 10¢ coin, a 25¢ safety switch 29, Fig. 11, is connected to terminal 115 of the 25¢ coin switch and is operated immediately after coin switch 14 is restored, thus preventing continued discharge of change coins in the event that the switch 14 is held closed by defective coins, debris, or other causes. When the switch 26 is operated it is apparent that the initial circuit established through the motor 17 and the electro-magnet 53 is opened and a circuit is completed from conductor 101 through blades 132 and 129, conductor 134, terminals 133 and 120 of switch 13, conductor 119, the now closed terminals 121 and 115 of switch 14, conductor 156, the now closed terminals 114 and

157 of switch 26, conductor 155, through relay coil 8 to conductor 91.

As in the case of the 10¢ coin, the permanent closure of coin switch 14 will, through the circuit above described, operate relay 8 and latching blades 132 and 106 in open position, thus preventing further operation of the change maker. Simultaneously the open blades 126 and 124 will de-energize reject magnets 9 and 11 and thus reject 10¢ and 25¢ coins subsequently deposited. Again, as in the case of the 10¢ coin, the closure of blades 106 and 129 will illuminate the "use nickel only" lamp 88.

When the cause of the permanent closure of switch 14 is corrected, the latch 125 of relay 8 is manually unlatched, thus returning all components of the change maker to their normal rest position, as shown Figs. 3 and 11.

Referring to Fig. 11, master switch 12 has an additional terminal 158, which in some cases may be used to initiate a well-known time delay circuit, not shown, for delaying the operation of the vending machine until a deposited coin has passed through the change maker.

Having described our invention we claim:

1. In a change making mechanism for operating an electrically initiated vending machine and for receiving gravity propelled coins of predetermined unit denomination and coins of a predetermined plurality of larger denominations, means forming a frame and a plurality of coin passageways, each of said passageways adapted to conduct each said coin of each denomination in a separate path, a momentary master electric switch for initiating the operation of said vending machine, said master switch responsive to the descent of each coin of each said denomination, a plurality of additional momentary electric coin switches positioned in said frame, corresponding with and responsive respectively to the descent in each of said passageways of each coin of each of said larger denominations, permanent magnet holding means positioned in said frame for temporarily and independently holding each of said additional coin switches in displaced position when operated by a coin corresponding thereto, a magazine for receiving and storing a predetermined minimum plurality of coins of said unit denomination deposited in said mechanism, electro-mechanical means for sequentially discharging coins of said unit value from said magazine, electro-mechanical motive means for restoring said electro-mechanical means including movable cam means for restoring each of said additional coin switches to normal position in predetermined sequence when held by said magnet holding means, a source of electric energy, circuit means connecting said source of energy, said vending machine, said master switch, said additional coin switches, said electro-mechanical means, said electro-mechanical motive means, whereby a coin of one of the said larger denominations deposited in said mechanism will momentarily operate said master switch and initiate through said circuit means the operation of said vending machine and upon its further descent will operate its said corresponding coin switch to energize through said circuit said electro-mechanical means and said electro-mechanical motive means and whereby said cam means will restore said electro-mechanical means and said coin switch when a predetermined number of coins of unit denomination has been discharged from said magazine.

2. In a change maker of the character described, means forming a frame and a passageway, said passageway adapted to conduct coins of predetermined large denomination, an electric coin switch in said frame positioned for operation by a coin descending in said passageway, magnet means for temporarily holding said coin switch in operated position, a magazine in said frame for storing a plurality of change coins of predetermined small denomination, electro-mechanical means for discharging a predetermined number of change coins from said magazine when energized a predetermined period, latching relay means for de-energizing said electro-mechanical means when energized, a safety switch normally completing a circuit to said electro-mechanical means adapted to de-energize said electro-mechanical means and simultaneously complete a circuit to energize said latching relay means when operated following the discharge of a predetermined number of said change coins, cam means in said frame driven by said electric motive means for restoring said coin switch and sequentially operating said safety switch following said predetermined period, a source of electric energy, circuit means connecting said coin switch, said electro-mechanical means, said safety switch, with said source of energy whereby the descent of a coin of large denomination will operate said coin switch and through said circuit means energize said electro-mechanical means to discharge a predetermined number of change coins from said magazine and whereby continued movement of said cam means will operate said safety switch to de-energize said electro-mechanical means when said circuit to said coin switch is not normally opened by said cam means.

3. In a change maker of the character described, means forming a frame and a passageway for conducting a plurality of coins of large denomination, a magazine in said frame for storing a quantity of change coins of predetermined small denomination, a coin switch positioned in said frame and operable by a coin of said large denomination descending in said passageway, holding means for holding said coin switch in operated position, electric motive means for sequentially discharging a predetermined plurality of said change coins when energized for a predetermined period, a safety switch connected in series with said coin switch for normally energizing said electric motive means when said coin switch is operated, cam means connected to and operated by said electric motive means for restoring said coin switch against the action of said holding means and successively operating said safety switch after the discharge of the said predetermined number of change coins, a source of electric energy, circuit means connecting said coin switch, said electric motive means and said safety switch with said source of energy, relay means connected in said circuit means for latching open said circuit means when energized, whereby the descent of said coin of larger denomination in said passageway will operate said coin switch and energize said electric motive means to discharge a predetermined number of change coins from said magazine and whereby said cam means will normally restore said coin switch and operate said safety switch following the discharge of said predetermined number of said change coins and whereby said safety switch will energize said relay and permanently de-energize said electric motive means when the

portion of said circuit means connected to said coin switch fails to open.

4. In an electric vending machine and an electric change maker therefor, vending machine circuit means for operating said vending machine one cycle when momentarily energized to discharge therefrom one unit of value, a safety vending relay connected in said vending machine circuit means for latching said circuit open when energized, a delivery switch connected in said vending machine circuit means for momentarily completing a portion of said vending machine circuit to said vending machine relay, and adapted to be operated by the delivery of each said unit of value, a first passageway means in said change maker for receiving and conducting unit value coins each corresponding to said unit of value, a second passageway means in said change maker for receiving and conducting in a separate path predetermined greater value coins, a momentary vending switch in said change maker adapted to be momentarily closed by the descent of coins of each said value, said vending switch connected in said vending circuit means for momentarily completing said vending machine circuit means and simultaneously completing a partial circuit to said safety vending relay when operated, a change maker circuit means, electro-mechanical means in said change maker and connected in said change maker circuit means for discharging a predetermined number of unit value coins when energized, a change maker switch in said change maker connected in said change maker circuit means and adapted to be closed by the descent of each of said greater value coins, said change maker switch adapted and constructed to be opened by said electro-mechanical means when a predetermined number of said unit value coins are discharged, a source of electric energy, an interconnecting circuit means connecting said source of electric energy said vending machine circuit means and said change maker circuit means whereby the descent of each of said greater value coins will momentarily close said vending switch to energize all said circuit means and operate said vending machine to deliver one unit of value and temporarily close said change maker switch to energize said change maker circuit means to operate said electro-mechanical means to discharge a predetermined number of unit value coins and whereby the permanent closure of said vending switch and the operation of said delivery switch will energize said safety vending relay to open said vending machine circuit and render said vending machine inoperative.

5. In an electric vending machine and an electric change maker therefor, vending machine circuit means for operating said vending machine one cycle when momentarily energized to discharge therefrom one unit of value, a first pas-

sageway means in said change maker for receiving and conducting unit value coins each corresponding to said unit of value, a second passageway means in said change maker for receiving and conducting in a separate path predetermined greater value coins, a momentary vending switch in said change maker adapted to be momentarily closed by the descent of each coin of each said value, said vending switch connected in said vending circuit means and adapted to energize said vending machine one cycle when momentarily closed, a change maker circuit means, a safety change maker relay connected in said change maker circuit means for latching said circuit open when energized, electro-mechanical means in said change maker and connected in said change maker circuit means for discharging a predetermined number of unit value coins when energized, a change maker switch in said change maker connected in said change maker circuit means and adapted to be temporarily closed by the descent of each of said greater value coins and adapted to be opened by the operation of said electro-mechanical means when the latter has discharged a predetermined number of unit value coins, a safety switch connected in said change maker circuit means for partially completing a portion of said change maker circuit to said change maker relay when operated by said electro-mechanical means, a source of electric energy, an interconnecting circuit means connecting said source of electric energy said vending machine circuit means and said change maker circuit means whereby the descent of each of said greater value coins will momentarily close said vending switch to energize all said circuit means and operate said vending machine to deliver one unit of value and close said change maker switch to energize said change maker circuit to operate said electro-mechanical means to discharge a predetermined number of unit value coins and whereby the permanent closure of said change maker switch and the operation of said safety switch by electro-mechanical means will complete a portion of said change maker circuit to energize said safety relay for opening said change maker circuit means to render said change maker inoperative.
